[57] ABSTRACT

A furnace for electrically heating thermoplastic material preferably including a chamber for containing a body of thermoplastic material defined by an upstanding peripheral wall and a bottom wall symmetric about a vertical center-line through the chamber; a first set of six electrode groups extending through the periph-

eral wall in generally the same horizontal plane, with each group having geometric center and with each group center being equidistant from adjacent group centers; a second set of six electrodes extending through the peripheral wall at generally the same height at those in the first electrode set, with each second set electrode being positioned equidistantly between adjacent first set group centers; and a supply circuit means for providing intraphase cross-firing current paths, through said thermoplastic material, between diametrically opposite first set electrode groups, intraphase peripheral-firing current paths between once-removed electrodes within the second electrode set, and interphase current paths between all electrodes not connected by intraphase current paths. The supply circuit means may include two sets of transformers having three transformers each and each set may have its transformers delta-connected to main-lines of a three-phase power source. The secondaries of one set of transformers is preferably double-delta connected to the six electrodes of the second electrode set, with the deltas thereof being reverse-phase rotated. The other transformer set has its secondaries connected across diametrically opposite pairs of first set electrode groups, with the electrodes in each group being connected in parallel to the respective transformer secondaries. The transformer secondaries may be provided with adjustable taps and two motors may be connected to the taps of respective transformer sets, whereby the taps of one transformer set may be multiply adjusted independently from the taps of the other transformer set.

ELECTRICAL FURNACE FOR MELTING THERMOPLASTIC MATERIAL

BACKGROUND OF THE INVENTION

1. Field of the Invention

This invention relates to apparatuses for heating thermoplastic material and more particularly to furnaces of the kind comprising a furnace chamber having a bottom wall and an upstanding peripheral wall for containing the thermoplastic material in its unmelted and molten states, electrodes spaced apart in plan for passing current through the thermoplastic material, and an electrical supply circuit for supply alternating electric current to the electrodes.

2. Prior Art

Electrically heated furnaces of the type described in U.S. Pat. No. 3,524,206, have recently been further developed for the purpose of melting relatively large volumes of glass-making materials. With such development, the diameter of the furnace chamber has been substantially increased; and in order to provide the additional electrical energy needed to melt the increased volume of thermoplastic material, more electrodes have been employed. Particularly, in lieu of the flush-type electrodes shown in the aforementioned patent, a relatively large plurality of rod-type electrodes have been used.

One of the major problems encountered in melting glass utilizing such a tank of large diameter and with a large number of electrodes is to attain heating of the body of thermoplastic material in as uniform a manner as possible, while yet specifically controlling the temperatures of the material adjacent the peripheral walls of the chamber so as to prevent undue erosion of the electrodes and of the peripheral walls of the chamber.

Also, another problem encountered was that of maintaining the conical shape of the fusion zone between the batch material and the molten thermoplastic material. The conical shape of the fusion zone, indicated as a line by reference numeral 23 in FIG. 1 is important, because the rate of melting, and hence the rate at which glass is produced by the furnace, is determined by the area of contact between the batch material 22 and the heated molten material 24.

Another problem relates to contamination of the refining zone of the furnace with unmelted or partially melted batch material. The refining or quiescent zone lies in the vicinity of the bottom wall of the chamber. The refining zone results from the fact that the temperature of the molten glass in the bottom part of the tank is substantially uniform horizontally, while a vertical temperature gradient exists in this part of the tank, the coolest glass being in the vicinity of the bottom wall of the tank. Contamination of this zone occurs when the fusion line is allowed to extend too deeply toward the bottom wall and also when the batch material is allowed to be drawn downwardly into this zone by convection currents along the peripheral walls of the tank between adjacent electrodes. Accordingly, it is necessary, at each rate of pull, to not only maintain the temperatures throughout the peripheral areas sufficiently high to prevent downward convection of unmelted batch material or unfined glass in this area, but it is also necessary to maintain the temperatures at the center of the melting zone of the chamber sufficiently high to

prevent over-extension of the central portion of the fusion zone.

- In the prior art furnaces, such as those disclosed in U.S. Pat. Nos. 3,585,861, 3,524,206, 3,440,321 and 5 2,993,079, electrodes positioned generally at the same height within the chamber were used to provide, through the thermoplastic material, either intraphase cross-firing current paths or intraphase peripheral-firing current paths, but not both intra-phase cross-firing and intraphase peripheral-firing current paths. A 10 shortcoming of those furnaces which have means for providing only intraphase cross-firing current paths was that the downward convective flow between electrodes could only be prevented by increasing the temperatures 15 in the vicinity of the electrodes; however, such increase substantially reduces electrode and wall life and also reduces the area of contact between the batch and molten material and thus causing a reduction in the melting rate of the tank.
- 20 In those furnaces having means for providing only intraphase peripheral-firing current paths between electrodes generally at the same chamber height, in order to provide sufficient heat in the center of the tank and thus to prevent the batch from descending therethrough into the refining zone, it was also necessary to increase the temperatures at the electrodes; and, in addition to the increased corrosion of the electrodes and adjacent wall portions, such increase in peripheral temperatures tends to melt away a peripheral portion of the 25 batch cover, thus allowing an undue amount of thermal energy to escape from the bath.

The main object of the present invention is to provide a new and improved apparatus for melting thermoplastic material better adapted to overcome these problems than these hitherto available.

SUMMARY OF THE INVENTION

The apparatus for electrically heating thermoplastic material of the present invention comprises a chamber for containing a body of thermoplastic material defined by a bottom wall and an upstanding peripheral wall symmetric about a vertical center-line through the geometric center of said bottom wall; first and second sets of six electrode means positioned generally symmetrically about said chamber center-line, for providing, respectively, through the thermoplastic material, intraphase cross-firing current paths and intraphase peripheral-firing current paths; and electrical supply circuit means for transmitting alternating electrical current to the electrode means from a polyphase electrical supply source, including two sets of voltage sources furnishing voltages of magnitudes and relative phases represented by voltage vectors corresponding at least approximately to lines joining all pairs of said electrode means, and first conductor means connecting one of said sets of voltage sources to said first set of electrode means for providing equal intraphase current flow between diametrically opposite pairs of first set electrode means, and second conductor means connecting the other set of voltage sources to said second set of electrode means for providing equal intraphase current flow between pairs once-removed second set electrode means and for providing uniform interphase current flow between all remaining pairs of electrode means.

The electrode means of said first and second sets of electrode means may be comprised of one or more rod-type electrodes. The six groups of first set electrode

means are positioned equidistantly from each other and symmetrically about the center-line of the furnace chamber. Each of second set electrode means are positioned equidistantly between said first set electrode means and also symmetrically about said chamber center-line.

The sets of voltage sources preferably include three transformers per set, with the primaries of each set of three transformers being delta-connected across the three main lines of a three phase source of electrical power. The three secondaries of one set are preferably connected across three pairs diametrically opposite first electrode means. The six secondaries of the other set of transformers are preferably double-delta connected, with reverse phase rotation between the deltas, to said six second set electrode means, with the first delta connected to three non-adjacent second set electrode means and with the second delta connected to the remaining second set electrode means.

The supply circuit means may further include regulator means for independently controlling the electrical energy supplied to respective first and second sets of electrode means. Such regulator means may include adjustable step transformers; that is, the transformers within said two sets of transformers may each have adjustably tapped secondaries, whereby the secondaries of one set of transformers may be multiply adjusted independently from the secondaries of the other set of transformers, and vice versa.

BRIEF DESCRIPTION OF THE DRAWINGS

FIG. 1 is a vertical sectional view of a furnace in accordance with a preferred embodiment of the invention.

FIG. 2 is a cross-sectional diagrammatic view of the furnace of FIG. 1, with, however, the thermoplastic material being removed for the sake of clarity, and also includes a schematic wiring diagram for an arrangement of electrodes employed therein.

FIG. 3 is a partial vertical sectional view of one embodiment of the present invention and illustrates an electrode arrangement wherein first and second sets of electrode means lie in two separate planes within the same heating zone.

FIG. 4 is a partial vertical sectional view of another embodiment of the furnace of the present invention and illustrates an electrode arrangement wherein the cross-firing first set of electrode means are positioned generally at the same height as that of the peripheral-firing second set of electrode means.

FIG. 5 is a voltage vector diagram representing the voltage relationships between the electrode means of the furnace, with the magnitudes of intraphase cross-firing and peripheral-firing voltages being equal.

FIG. 6 is a vector diagram depicting the voltage relationships between the electrode means of the furnace, with, however, the magnitude of the intraphase cross-firing voltages being greater than the magnitude of the intraphase peripheral-firing voltages.

DESCRIPTION OF THE PREFERRED EMBODIMENTS

Referring initially to FIGS. 1, 2 and 3, the furnace illustrated diagrammatically therein may be generally as described and illustrated in U.S. Pat. No. 3,524,206, except for certain modifications in the form and arrangements and numbers of electrodes employed

therein and the supply circuit for feeding current to the electrodes.

The furnace chamber 14 may be generally circular in form having a bottom wall 16 and an upstanding peripheral wall 18 formed of any suitable refractory material. Peripheral wall 18 is symmetrical about center-line 17. Batch material 22 is fed into the furnace through the top of the furnace by suitable batch feeder means, which may be a batch container having means for agitating the batch. Batch material 22 forms a batch cover 25 covering most or all molten thermoplastic material 24. The batch is preferably continuously fed into the furnace and molten thermoplastic material is continuously withdrawn through outlet 20 at the center of the bottom wall of the furnace. Batch 22 forms a fusion zone or surface depicted by line 23 of generally a conical shape with molten material 24.

Disposed in the chamber 14 within a given heating zone are a plurality of electrode means designated 1 to 12. The electrode means may each be comprised of one or more flush-type or rod-type electrodes, and with regard to rod-type electrodes, their size depth of immersion and arrangement will vary according to size and shape of the chamber and type of thermoplastic material to be melted. The electrode means 1 to 6 constitute a first cross-firing set of electrode means, with each electrode means therein preferably including three rod-type electrodes designated a, b and c respectively. The electrode means 7 to 12 constitute a second peripheral-firing set of electrode means, with each electrode means therein preferably including one rod-type electrode; however, each electrode means 7-12 may include more than one electrode. As shown in FIGS. 3 and 4 each of the electrodes a, b and c of the first set of electrode means 1 through 6 may be disposed within the same heating zone above bottom wall 16. As illustrated in FIG. 3 each of the electrodes d within the second set of electrode means 7 through 12 may be positioned at a height below the plane of electrodes within said first set; or, as shown in FIG. 4 the electrodes of electrode means 7 to 12 may be positioned at the same height above bottom wall 16 as that of electrodes a, b and c of electrode means 1 to 6.

As shown in FIG. 2, electrode b within electrode means 1 to 6 is positioned at the elevational geometrical center C₁ of said means. As shown in FIG. 2, the first set of electrode means 1 to 6 are positioned about the periphery of chamber 14 such that the geometrical centers C₁, or electrodes b, of each electrode means 1 to 6 are equidistant from the centers of the two adjacent first set means centers.

Since the preferred embodiments of the invention includes only one electrode d in each electrode means of the second set of electrode means 7 through 12, the elevational geometric center C₂ of the second means are located at the geometric centers of electrodes. Each second set electrode means is peripherally positioned within chamber 14 midway between the geometric centers of said first set electrode means such that each of the centers C₂ of said second set means are equidistant from adjacent centers C₁ of said first set means. In such a configuration, centers C₂ are also positioned equiangularly between adjacent centers C₁.

Current is fed to the first and second set of electrode means from a polyphase electrical supply system which may be the main supply available in the area in which the furnace is in operation. In this case such system

would normally be a three phase supply system. In FIG. 2 main lines of three-power phases of a standard main line supply are indicated by reference numerals L₁, L₂ and L₃.

The current is fed from this system to the electrode means through the intermediary supply circuit adapted to provide two independently controllable sets of voltages sources, such that voltage supplied to the electrode means of the first cross-firing set of electrode means 1 to 6 may be controlled independently from that supplied to the second peripheral-firing set of electrode means 7 to 12. More specifically, the supply circuit means includes a first set of voltage sources adapted to provide intraphase cross-firing current paths, shown at least approximately as dashed lines in FIG. 2, between diametrically opposite electrode means of said first electrode means set, that is, between electrode means 5 and 2, 1 and 4, and 3 and 6. The supply circuit means further includes a second set of voltage sources adapted to provide intraphase peripheral-firing paths between once-removed electrode means within respective second electrode means sets 7-12, that is, as shown at least approximately by solid lines in FIG. 2, between electrode means 7 and 9, 7 and 11, 8 and 10, 8 and 12, 9 and 11, and 12 and 10. The supply circuit means also preferably includes means for varying the voltages supplied to said first cross-firing set of electrode means independently from that supplied to said second peripheral-firing electrode means set; this independence of control permits the relative increase or decrease of the current density along said intraphase cross-firing or peripheral-firing paths, thus allowing responsive control of temperatures in the peripheral area of chamber independently from those temperatures in the central area of the bath, and vice versa. Also, as will be discussed below, at each respective setting, the intraphase and interphase voltages between all electrode means remains symmetrical about the center-line 17 of chamber 14.

The first set of voltages sources preferably includes a first set transformer T1 having three primary windings 21, 23 and 25 which are delta connected across main lines L₁, L₂ and L₃. The secondary windings of said first set transformer T1, indicated at reference numerals 22, 24 and 26, are connected to diametrically opposite electrode means within said first electrode means set; that is, secondary winding 22 is connected to electrode means 1 and 4, winding 24 is connected to electrode means 3 and 6, and winding 26 is connected across electrode means 5 and 2. Within each electrode means, electrodes a, b and c thereof are connected in parallel to the respective terminals of said secondary windings.

The second set of voltage sources may include a second set transformers T2 having three primary windings 27, 30 and 33 which are delta connected across main lines L₁, L₂ and L₃, respectively. The secondary windings of said second set of transformers T2, indicated at reference numerals 28, 29, 31, 32, 34 and 35, are double delta connected to said second set electrode means, with reverse phase rotation between each of the two deltas so that secondary windings 29, 32 and 35 comprise one delta connection and secondary windings 28, 31 and 34 comprise the other delta connection, its phase rotation being reversed from said first-mentioned delta connection. More specifically, secondary windings 29, 32 and 35 are delta connected respectively

across once-removed second set electrode means 10 and 8, 12 and 10, and 8 and 12. Similarly, but with reverse phase rotation, secondary windings 28, 31 and 34 are delta connected respectively across electrode means 7 and 9, 9 and 11, and 11 and 7.

The secondary windings of transformers T1 and T2 may be provided with adjustable-step taps. Two servomotors, each connected respectively to the secondary winding taps of the transformers T1 and T2, may be used to multiply adjust the taps of said first set of voltage sources independently from those of said second set of voltage sources, and vice versa. Alternatively buck-boost regulator means, such as saturable reactors or variable auto-transformers may be connected between transformers T1 and T2 and main lines L₁, L₂ and L₃ in order to independently control the polyphase electrical power supplied to transformers T1 and T2. However, in order to ensure that the phase voltages applied across each of the electrode means of said first and second electrode means sets is uniform and symmetrical about center-line 17, the turns ratio of each of the primary and secondary windings within each transformer T1 and T2 should be selected to provide voltages of equal magnitude across the secondary windings of transformer T1 and, similarly, but not necessarily same voltages as those of transformer set T1, voltages equal magnitude across the secondaries of transformer set T2.

The magnitudes of cross-firing voltages furnished by secondary windings 22, 24 and 26 are equal to each other, as represented by the phase voltage vectors or phasors V₁, V₂ and V₃ in FIGS. 5 and 6, with vectors V₁, V₂ and V₃ representing the respective voltages between electrode means 5 and 2, 1 and 4, and 3 and 6. The voltages furnished by secondaries 29, 32 and 35 of transformer T2 are also equal to each other, as is represented by voltage vectors V₄, V₅ and V₆, respectively. The voltages furnished by secondaries 28, 31 and 34 are equal to each other and to the voltages provided by secondary windings 29, 32 and 35, as is represented by vectors V₇, V₈ and V₉.

The voltage vector diagram of FIGS. 5 and 6 illustrate not only the symmetry of the intraphase cross-firing, represented by vectors V₁, V₂ and V₃, and of the intraphase peripheral-firing, represented by vectors V₄ through V₆; but they further depict the symmetry of the interphase voltages about the center-point 0 between electrode means of the first set shown in part by V_b and V_d; between electrode means of the second set shown in part by V_f and V_g; between electrode means of the first set and electrode means of the second set shown in part by V_a, V_c, V_e. As shown by FIG. 5, wherein the magnitude of vectors V₁, V₂ and V₃ each has been increased, both the intraphase and interphase voltage vectors remain symmetrical about center point 0, even though the magnitude of potential across the cross-firing paths between the first set of electrode means has been increased independently from the magnitude of potential applied across the peripheral-firing paths of second set of electrode means.

It will be seen from FIGS. 5 and 6 that cross-firing vectors V₁, V₂ and V₃ intersect at point 0 and form 60° angles between each other. The figures constructed by vectors V₄ - V₆ and V₇ - V₉ correspond to two equilateral triangles having their apexes equidistant between vectors V₁, V₂ and V₃; thus a line, 1, connecting these apexes with point 0 would be separated from adjacent

cross-firing vectors by 30°. FIGS. 5 and 6 illustrate the relationships of the interphase voltages between electrode means. The magnitude of interphase voltages V_a through V_e can be determined according to well-known formulas defining the lengths of sides of triangles. For example, the magnitude of voltages V_a between any two adjacent electrodes can be computed according to the following formula:

$$V_a = 1/2(V_{cf}^2 - 2V_{cf}V_{pf} + 4/3V_{pf}^2)^{1/2}$$

where V_{cf} equals the magnitude of vectors V_1 , V_2 and V_3 and V_{pf} equals the magnitude of vectors V_4 through V_9 . Similarly, the magnitude of interphase vectors V_b through V_e may be determined as a function of magnitudes of vectors, V_{cf} and V_{pf} , that is, as a function of the magnitudes or potential across the secondary windings of said sets of transformers T1 and T2, respectively.

More specifically, in order to obtain a symmetrical distribution of intraphase cross-firing and peripheral firing current paths and interphase current paths between the twelve electrode means about center-line 17, as shown in FIG. 2, it is not necessary to adhere to strict identity between the polygonal figure constructed by dashed lines joining electrode means 1, 7, 2, 8, 3, 9, 4, 10, 5, 11, 6, and 12 as shown in FIGS. 5 and 6, and the polygonal figure within which peripherally outermost interphase voltage vectors, V_a , would be drawn as shown in FIG. 4. Rather in practice, the magnitudes of vectors V_1 , V_2 and V_3 may be increased independently from the voltages of vectors V_4 through V_9 , as shown in FIG. 5, with the resulting vector diagram, as shown in FIG. 6, depicting a polygonal figure within which vectors V_a would be drawn being different from the polygonal figure constructed by joining the aforementioned electrodes.

It should be noted that the first and second sets of electrode means may lie in two planes or may lie at same general height above the chamber bottom wall. It is only essential that there be interphase firing between all respective electrode means within each of the first and second sets, that is, between electrode means not connected by said interphase cross-firing and peripheral-firing paths within each respective set. It will be appreciated that such interphase firing paths, in conjunction with the intraphase firing paths, constituting a heating zone. That is, a heating zone is that area within the bath wherein the sets of electrode means are not electrically isolated from one another.

More than one heating zone may be utilized to control the heating and fining of the thermoplastic material. As shown in FIG. 1, three zones may be used, with the uppermost and middle zone being utilized to melt and fine the thermoplastic material and the lowermost zone being used during the start-up procedure.

Inasmuch as the foregoing descriptions have been provided solely as those of preferred embodiments of the invention, the scope of the invention is not to be limited thereby but is intended to be limited only by the scope of the appended claims.

We claim:

1. A furnace for electrically heating thermoplastic material comprising:
  - a bottom wall and an upstanding peripheral wall symmetric about a center-line, with said bottom and peripheral walls defining a chamber for containing a body of thermoplastic material to be melted;

- a first set of six equidistantly spaced means for providing, through said thermoplastic material, at least three cross-firing current paths intersecting in the vicinity of said center-line;
- a second set of six electrode means for providing, through said thermoplastic material, intraphase peripheral-firing current paths, being symmetric about said center-line; and
- supply circuit means for transmitting alternating electrical current to said first and second set electrode means, including
  1. a supply of polyphase electrical power;
  2. first and second sets of voltage sources fed by said supply, with said first voltage source set furnishing intraphase voltages of respectively equal magnitude and relative phases represented by voltage vectors corresponding at least approximately to lines joining said first set electrode means and with said second voltage source set furnishing intraphase voltages of respectively equal magnitude and relative phases represented by voltage vectors corresponding at least approximately to lines joining said second set electrode means; and
  3. conductor means for connecting said first and second sets of voltage sources respectively to said first and second sets of electrode means to apply voltages of respectively equal magnitudes across said at least three cross-firing paths, to apply voltages of respectively equal magnitudes across said symmetric peripheral-firing paths, and voltages of respectively equal magnitudes between all corresponding pairs of electrode means not connected by said intraphase cross-firing and peripheral-firing current paths.

2. The furnace of claim 1 wherein said supply circuit means includes regulator means for independently controlling the magnitudes of intraphase voltages supplied by each respective set of voltage sources, whereby the electrical energy provided along said intraphase cross-firing and peripheral-firing paths may be separately regulated.

3. The furnace of claim 1 wherein each said first set electrode means is positioned equidistantly from adjacent electrode means of said first set and each of said second set electrode means is positioned equidistantly between adjacent first set electrode means.

4. The furnace of claim 1 wherein the geometric center of each electrode means within said first and second set of electrode means lie generally at the same height above said bottom wall.

5. The furnace of claim 1 wherein said polyphase source supplies three phases, and said two sets of voltage sources include respective first and second sets of transformers, and said connector means includes

- a in said first set of transformers, three secondaries being connected across three diametrically opposite pairs of electrode means within said first electrode means set, and
- b. in said second set of transformers, three secondaries being closed delta connected to three once-removed electrode means within said second set of electrode means, and three additional secondaries being closed-delta connected to the other three electrode means with said second set of electrode means, with the voltage phases between the other three electrode means being reversed from the

voltage phases of said first-mentioned three electrode means.

6. A furnace for melting and for electrically heating thermoplastic material comprising:

- a. a chamber, for containing a body of thermoplastic material, defined by a bottom wall and an upstanding wall symmetrical about a vertical center-line; 5
- b. a first set of six electrode groups extending through said peripheral wall, with each group having a geometric center and with each group center lying in generally the same plane and being equidistant from adjacent group centers; 10
- c. a second set of six electrodes extending through said peripheral wall, with each second set electrode being positioned equidistantly between adjacent first set group centers; and 15
- d. supply circuit means for providing, through said thermoplastic material, intraphase cross-firing current paths between diametrically opposite first set electrode groups, intraphase peripheral-firing current paths between once-removed electrodes within said second set of electrodes, and interphase current paths between all first set groups and second set electrodes not connected by said intraphase cross-firing and peripheral firing current paths. 20

5

10

15

20

25

7. The furnace of claim 6 wherein said supply circuit means includes:

- a. a supply of polyphase power;
- b. two sets of voltage sources fed by said supply furnishing voltages of magnitudes and relative phases represented by intraphase and interphase voltage vectors being symmetrical about a center-line corresponding to said vertical center-line; and
- c. conductor means for connecting said sets of voltage sources to said first and second sets of electrodes to apply intraphase voltages of a first magnitude across said cross-firing paths between said diametrically opposite first set electrode groups, to apply intraphase voltage of a second magnitude across said peripheral-firing paths between once-removed electrodes within said second electrode set, and to apply interphase voltage between all first set groups and second set electrodes not connected by said intraphase cross-firing and peripheral firing paths.

8. The furnace of claim 6 further including regulator means for separately controlling the amount of electrical energy provided along said intraphase cross-firing paths and the amount of energy provided along said intraphase peripheral-firing paths.
